UNITED STATES PATENT OFFICE

WILLIAM D. THOMAS, OF LYNNFIELD, MASSACHUSETTS, ASSIGNOR TO UNITED SHOE MACHINERY CORPORATION, OF PATERSON, NEW JERSEY, A CORPORATION OF NEW JERSEY

SHOE TURNING MACHINE

Application filed June 29, 1929. Serial No. 374,762.

This invention relates to shoe turning machines and is herein illustrated as embodied in a shoe turning machine in which the forepart of a shoe is turned by power-operated 5 instrumentalities.

Turn shoes are sewed wrong side out and after the sewing has been completed they are commonly turned right side out by machines of the type disclosed in the application for 10 United States Letters Patent of Edward Erickson, Serial No. 733,112, filed August 20, 1924. In machines of the type disclosed in the above-mentioned application co-operating heel turning members are first operated 15 to turn the heel part of a shoe and are thereafter locked in position to clamp the heel seat of the shoe and thereby hold the shoe firmly during the subsequent turning of the forepart.

20 The forepart turning instrumentalities of machines of the above-mentioned type comprise a sole support over which the sole of the shoe is bent by the operator after the heel seat has been clamped, a turning iron 25 arranged to engage the toe of the upper, and a forepart spreader which is normally maintained in an out-of-the-way position and is manually inserted in the forepart of the shoe before the forepart turning operation is 30 commenced. The turning iron of such a machine is first moved into engagement with the toe of the shoe and thereafter all three members are moved simultaneously in the same direction to effect the turning of the 35 forepart of the shoe, the turning iron moving at twice the speed of the sole support and the forepart spreader being merely pushed out of the way by the turning iron. As a result the forepart of the shoe is gradually 40 stripped off from the forepart spreader and turned right side out upon the turning iron. Continued operation of the machine under power serves to retract the turning iron and the sole support to their initial positions, to 45 unlock the heel turning members from their clamping positions, and to release the forepart spreader to enable it to be returned to its normal out-of-the-way position, thereby completing a cycle of operations.

50 In certain styles of shoes, such as various

strap shoes and pumps which have recently been made in considerable quantities, the throat opening through which the sole has to be passed to accomplish the turning of the forepart of the shoe is liable to be smaller 55 than in shoes as commonly designed heretofore and, because of the improved design and tighter lasting of the upper materials, this throat opening is usually less readily adaptable to accommodate the passage there- 60 through of the widest portion of the sole. In these recently designed shoes, accordingly, it is often unusually difficult to turn the foreparts without tearing or otherwise injuring 65 the uppers.

One object of the present invention is to provide an improved shoe turning machine of the type referred to which will be as satisfactory in operation for turning shoes of the types heretofore made as the machines formerly employed but which will be even better adapted for turning the newer types of shoes with the smaller throat openings above mentioned.

With this object in view, one feature of the present invention consists in the provision, in a shoe turning machine, of two members constructed and arranged to co-operate in turning a shoe, and operating mechanism for said members constructed and arranged to impart an operative movement to one of the members and, simultaneously with the initiation of said operative movement, to move the other turning member at a different speed from that of the first member to cause it to co-operate with the first member, such an organization insuring improved co-operation of the shoe turning members for the purpose of insuring that the shoe uppers will not be subjected to excessive strain during the turning operation and particularly to facilitate the passage of the widest portion of a sole through the narrow throat opening of the upper. In the illustrated machine improved co-operation of two forepart turning members consisting of a turning iron and a sole support is insured by the combination with a carrier upon which said members are movably mounted, of a rack bar movable relatively to the carrier, clutch mechanism

for connecting the sole support, the carrier and the rack bar for movement in unison, and gearing in continuous driving engagement with the rack bar and with the turning iron and operable simultaneously with the initiation of the movement of the sole support to move the turning iron at twice the speed of the sole support to co-operate with the sole support in turning the forepart of the shoe. While the above-defined organization provides for the effective turning of the forepart of a shoe without risk of injury to the shoe upper under most conditions, nevertheless, for the purpose of further insuring against possible injury to shoes which for certain reasons may be unusually difficult to turn the illustrated machine is provided with a sensitive friction clutch which is interposed between the turning instrumentalities and the source of power, and the members of which are adjustable to adapt them to slip under different load conditions.

In accordance with another feature of the invention, as herein illustrated, the means controlled by the actuation of the forepart turning means for locking the heel turning members to clamp the heel seat of the shoe includes a roll clutch, a clutch of this type having been found most reliable for this particular purpose because it exerts its full clutching engagement without any yielding movement on the part of the members which it engages, and thereby eliminates any tendency on the part of the turning members to ease up in their clamping pressure upon the heel seat.

In accordance with a further feature of the invention an improved mechanism for controlling the stopping and starting of the machine is provided. This control mechanism has a manually operable member whereby the operator can actuate the mechanism to start the machine, the mechanism itself being constructed and arranged to stop the machine automatically upon the completion of a cycle, even if the operator inadvertently should retain his grasp upon the control member and hold this member in starting position. In addition to the above-mentioned mechanism, and associated therewith, the illustrated machine is provided with operator-controlled means for disengaging the driving means from the shoe turning means, an advantage of this additional feature being that it enables the operator to stop the machine at any point in the cycle of operations when he thinks it necessary to avoid injury to a shoe.

Other features of the invention consist in the provision of improved adjustments for the forepart spreader and for the heel turning instrumentalities and in certain novel features of construction and combinations and arrangements of parts hereinafter described and claimed, the advantages of

which will be obvious to those skilled in the art.

In the accompanying drawings, illustrating a preferred form of the invention,

Fig. 11 is a sectional view taken on the line XI—XI of Fig. 1;

Fig. 12 is an enlarged side elevational view showing the shoe turning instrumentalities of the machine in operation upon a shoe; and

Fig. 13 is a view similar in all respects to Fig. 12 except that the shoe turning instrumentalities are shown at a further stage in the turning operation.

The illustrated machine is provided with instrumentalities which operate first to turn the heel portion of a shoe and then to hold the heel portion clamped while other instrumentalities of the machine operate to turn the forepart. The various turning instrumentalities are carried upon a head 20 (Fig. 1) which is mounted upon a standard 22.

For turning the heel portion of the shoe a plurality of stationary members 24 (Figs. 1, 4, 12 and 13) which are designed for operation upon various types of shoes respectively are carried by a turret 26 which is mounted for rotation in a horizontal plane upon the head 20. In order to hold the turret 26 in position to maintain any one of the stationary heel turning members 24 in operating position, a spring latch 28 is mounted upon the head 20 so as to engage one of a plurality of recesses 30 formed in the turret 26. The shanks of the stationary turning members 24 are received in sockets 32 which are clamped in an arcuate slot 34 formed in the turret 26 and are secured in this slot by means of clamping bolts 36. This arrangement provides for adjustment of the stationary members 24 with respect to the turret 26 and about

the axis thereof. The stationary members 24 may also be adjusted by rotation about the axes of the sockets 32 by loosening the bolts 38 which clamp the shanks of the stationary 5 members 24 in the sockets. Screws 40 secured in the sockets 32 are threaded into the ends of the shanks of the stationary members 24 and thus serve as stop members when the shanks are inserted in the sockets to provide 10 for longitudinal adjustment of these members, that is, adjustment of the radial distances between the axis of the turret 26 and each of the stationary heel turning members 24. Cooperating with the stationary heel 15 turning members 24 are a plurality of heel cups 42 which are designed for operation upon various types of shoes respectively, and which are carried upon a turret 44 mounted on a lever 46 which is fulcrumed at 48 upon 20 the head 20. The lever 46 may be swung about its fulcrum to bring one of the heel cups 42 into engagement with one of the stationary heel turning members 24 by means of a rod 50 connected to a treadle lever 52 25 having a hinged extension 54 which carries a treadle. A spring 56 normally holds the treadle lever 52 up and the cup members 42 down and away from the stationary heel turning members 24. A spring 58 surrounding 30 the rod 50 and interposed between an abutment on the head 20 and a nut on the rod 50 serves to cushion the downward movement of the various members carried by the lever 46 when the treadle 54 is released by the operator. The heel cups 42 are adjustably 35 carried upon the turret 44 by means of bolts 60 which extend through slots formed in the turret 44. The turret 44 may be rotated about its axis to bring any one of the several 40 heel cups 42 into operative relation with respect to the desired stationary member 24 which has already been secured in operative position. A spring latch 62 (Fig. 13) serves to hold the turret 44 in one of a plurality of 45 positions to maintain a selected heel cup in operative relation to a selected stationary heel turning member. A clamping bolt 64 is employed to exert pressure through a cap 66 and thereby clamp the hub of the turret 44 50 as a further security against undesired movement. The turning of the heel portion of a shoe S (Figs. 12 and 13) is accomplished by bringing a selectively positioned heel cup 42 with the shoe supported thereon toward a 55 selectively positioned stationary member 24, causing the stationary member 24 first to be engaged by the heel-seat of the sole of the shoe and then to be received within the heel cup 42, carrying the sole along with it and 60 turning the upper over the edges of the heel cup. Mechanism later to be described is provided for maintaining the turret 44 in the position which it assumes at the completion of 65 the heel turning operation, for the purpose of clamping the heel-seat of the shoe against the

stationary member 24 to hold the shoe firmly in position for operation by the forepart turning instrumentalities.

After the turning of the heel portion has been completed, the shoe S is held clamped, 70 the heel-seat lying in a substantially vertical plane, as shown in Figs. 12 and 13, with the forepart of the shoe extending upwardly in convenient position for the operation of the forepart turning instrumentalities, which consist of a sole support 68, an upper or forepart spreader 70 and a turning iron 72, together with their respective supporting and actuating means which will presently be described. The upwardly extending sole of the shoe is bent about the forward end of the sole support 68 which extends horizontally, and the forepart spreader 70 is then inserted into the forepart of the shoe to maintain the forepart distended and to hold the shoe in 80 position for operation thereupon by the turning iron 72 and the sole support 68. Power-actuated mechanism is then started to cause an advancing movement first of the turning iron 72 to bring it into engagement 85 with the toe of the shoe and then of both the turning iron 72 and the sole support 68 to turn the forepart of the shoe. In order to permit the forepart spreader 70 to move in unison with the turning iron 72 and also to 90 guide it in the path of travel of the turning iron 72, the forepart spreader 70 is carried by a rod 74 which slides within a bearing 76 fulcrumed at 78 on a cover 121 secured to the head 20. The bearing 76 is normally 95 maintained tilted upwardly about its fulcrum 78 in order to swing the forepart spreader 70 out of the operator's way during the turning of the heel portion of the shoe. The forepart spreader 70 may be manually 100 brought down by the operator for insertion into the forepart of the shoe for the purposes above stated, and mechanism presently to be described is provided for holding the bearing 76 down and thereby holding the forepart 105 spreader 70 down in horizontal or operative position. In order to facilitate manipulation of the forepart spreader 70, the latter is supported in a handle 80 of the "pistol grip" type 110 which is adjustably attached upon the forward end of the rod 74. The shank portion of the forepart spreader 70 is provided with a slot 82 (Figs. 8 and 9) through which extends a clamping pin 84, thereby permitting longitudinal adjustment of the forepart 115 spreader 70. The shank of the forepart spreader 70 is curved in cross-section and is received against a concavely curved face 120 formed in the lower face of the pistol grip 80. As shown in Figs. 8 and 9, the slot 82 is relatively wide and the pin 84 is of relatively narrow diameter, thereby permitting a rotary movement of the curved shank with respect to the curved bearing surface for 125 adjustment of the forepart spreader 70 about 130

its own longitudinal axis. The bolt 84 is provided with a head 86 which engages the under side of the shank portion of the forepart spreader 70 to clamp the shank of the latter against the curved bearing surface of the pistol grip 80. Provision is also made for tilting adjustment of the forepart spreader 70 upwardly or downwardly by mounting the pistol grip 80 upon a fulcrum 88 secured upon a sleeve 90 which is clamped upon the end of the rod 74. An extension 92 of the pistol grip 80 is provided with a slot 94 which receives an eccentric 96 journaled in a lug 98 formed in the sleeve 90. Rotation of the eccentric 96 is effected by means of a handle 100 to swing the pistol grip 80 and the forepart spreader 70 in a vertical plane. The fulcrum pin 88 forms a part of the pistol grip 80 and a portion 102 of the pin 88 is reduced in diameter to accommodate a set-screw 104 for securing it in adjusted position. The reduced portion 102 is longer than the diameter of the set-screw 104 in order to provide longitudinal adjustment of the pin 88, thereby permitting translatory adjusting movement of the forepart spreader 70 in a direction transverse to the direction of movement of the turning iron 72. A set-screw 106 is employed to clamp the eccentric 92 in adjusted position. A pair of grooved wheels 108 are journaled in the free end of the bearing 70 to permit the rod 74 to travel thereon with a minimum of friction. A single grooved wheel (not shown) is mounted on the fulcrum pin 78 and carries the weight of the rod 74 at this point. For guiding the rod 74 a lever 110 is fulcrumed upon the head 20 and has its free end connected by a link 112 to the rear end of the rod 74. In order to cushion the rod 74 when it slides backward upon upward tilting movement of the bearing 76, a pin 114 (Fig. 2) is slidably carried in the lever 110, the latter having an extension which gives it the form of a V-shaped bell-crank to provide spaced bearings for the pin 114. The end of the pin 114 engages a fixed abutment 116 formed on the head 20, the end of this pin being urged outwardly by a spring 118 which surrounds the pin 114 and is secured thereto at one end, the other end of the spring 118 engaging the bearing for the pin 114 which is carried upon the main arm of the lever 110. The spring 118 thus serves to take up the shock when the end of the pin 114 engages the abutment 116. The above-mentioned sole support 68 and turning iron 72 are carried upon a slide 120 which is mounted for reciprocation in a horizontal plane in guideways 122 formed by the head 20 and the cover 121 (Fig. 5). The sole support 68 consists of an elongated member or bar, and the toe turning iron 72 consists of a member appropriately formed both to bear against the toe of the shoe at the beginning of the turning operation and to enter the toe

of the shoe at the completion of the turning operation and is threadedly adjustable in a bar 124, the latter constituting a rearward extension of the turning iron 72. The bar 124 slides upon the sole support 68 and the turning iron 72 is provided with a depending guide member 125 (Fig. 2) which enters into an undercut slot 126 formed in the sole support 68 for the purpose of guiding the turning iron 72 in its movement and also for holding it against upward movement with respect to the sole support 68. The sole support 68, with the bar 124 upon it, is slidably carried upon a bar 128 which is notched to receive the sole support 68. The bars 124 and 128 and the sole support 68 are thus all carried by the slide 120 and are each slidable with respect to the others and to the slide 120, which is provided with guide walls on each of its sides for preventing lateral displacement of the slideable members which it carries, and also with a flat cross-piece 129 for holding these members down. The turning bar 124 and the bar 128 each have a lateral face provided with rack teeth 130 and 132 respectively. The bar 128 does not operate directly upon the shoe and will herein-after be termed a rack bar to distinguish it from the bar 124 of the turning iron 72. Mounted for free rotation upon a shaft 134 secured in the cover 121 (Figs. 5 and 2) is an integral member comprising a pair of pinions 136 and 138, the pinion 136 having a pitch diameter equal to twice the pitch diameter of the pinion 138. The pinion 136 is constantly in mesh with the rack teeth 130 formed upon the bar 124 of the turning iron 72, while the pinion 138 is constantly in mesh with the rack teeth 132 formed upon the rack bar 128 and, because the pinions 136 and 138 constitute a unitary member and rotate about a fixed axis, the travel of the turning iron 72 and of the rack bar 128 will necessarily be interdependent and at the predetermined ratio of 2 to 1. The initial position of the sole support 68, that is, the position at which it is desired to maintain this support when the sole of the shoe is bent over its operative or forward end preparatory to inserting the forepart spreader 70 in the upper of the shoe, is determined by an adjusting screw 140 which is threaded in a bracket 142 extending from the rear portion of the head 20 in a position to enable the screw 140 to abut the rear end of the sole support 68. A roll 159 (Figs. 12 and 13) supports the forward portion of the sole support 68. The roll 159 is journaled in a bracket which, as shown in Fig. 1, is pivotally mounted upon the head 20 and extends forwardly therefrom, and carries a depending abutment screw which rests upon the top of the fulcrum pin of the turret 26 for supporting this bracket in a height-wise adjustable position. After the forepart spreader has been inserted in the shoe as

above described, the turning iron 72 is advanced into engagement with the toe of the shoe. This movement of the turning iron 72 is effected by the advance of the slide 120 by power-driven mechanism later to be described. Driving engagement between the slide 120 and the bar 124 of the turning iron 72 is effected through an abutment 144 mounted upon the bar 124 and a lever 146 fulcrumed upon a bracket 148 which is carried upon the slide 120. The lever 146 extends downwardly from its fulcrum and is notched to accommodate the bars 124 and 128 and the sole support 68, one edge of the notch being engageable with the abutment 144. As the lever 146 is freely pivoted upon the bracket 148, a spring 150 is interposed between the bracket 148 and the lever 146 to exert a yielding driving thrust upon the bar 124, such thrust being sufficient to drive the turning bar 124 against ordinary frictional resistance until the turning iron 72 encounters the toe end of the shoe on the forepart spreader 70. Mounted upon the lower end of the lever 146 and beneath the rack bar 128 is a transversely extending finger 152, which normally bears against a shoulder on the slide 120 to maintain the lever 146 normally in a vertical position against the force of the spring 150. Formed upon the slide 120 and extending rearwardly with an upward inclination is a guideway 154 for a clutch roll 156 which is normally urged downward in the guideway 154 by a weak compression spring 157. The backward yielding of the lever 146, when the turning iron 72 encounters the resistance of the shoe, will cause the finger 152 to jam the clutch roll 156 rearwardly and up the inclination of the guideway 154, causing the roll to exert an upward pressure on the rack bar 128 and, through the latter, upon the sole support 68. The upper surface of the sole support 68 will thus be clamped against the under face of the bracket 148. As shown in Fig. 5, the upper surface of the sole support 68 is slightly higher than the upper surface of the rack bar 128 to provide a reasonable clearance between the latter and the under surface of the bracket 148, so that not merely the rack bar, but both the rack bar and the sole support will be clamped to the slide 120. Sufficient clearance is provided in the bracket 148 for the free passage of the bar 124 even when the rack bar 128 and the sole support 68 are thus clamped. The operation of the clutch roll 156 as above described serves to clamp together the slide 120, the sole support 68, and the rack bar 128, thereby causing both the sole support 68, which has hitherto remained stationary, and the rack bar 128 to advance in unison with the slide 120 and causing the turning iron 72 to be advanced at twice the speed of the rack bar 128, and therefore of the sole support 68 and the slide 120, through the pinions 136

and 138. While the advance of the turning iron 72 at a relatively greater speed than that of the slide 120 will carry the abutment 144 ahead of and away from the lever 146, the roll 156 nevertheless will be held locked by reason of the rearward thrust of the rack bar 128 upon it.

Upon the completion of its advance movement, the slide 120 is retracted to its initial position by the same power-driven mechanism which caused it to advance. Ordinarily the roll 156 remains locked during the rearward movement of the slide 120, and the sole support 68 and the rack bar 128 will be brought back with it, while the bar 124 of the turning iron 72 will be returned at twice the speed of the slide. The return of the turning iron 72 will now restore the abutment 144 to its initial position in engagement with the lever 146. The abutment 144 engages the lever 146 slightly before the movement of the sole support 68 is arrested by the stop screw 140, and the resistance of the spring 150, acting through the lever 146, the bar 124 of the turning iron, the gears 136 and 138 and finally upon the rack bar 128, will roll the clutch roll 156 forward relatively to the slide and thereby release its clamping action. Even if, however, the release of the roll 156 were not to be effected thus, the rearward movement of the sole support 68 would be arrested by engagement with the stop screw 140, and the sole support 68 would tend to hold the rack bar 128 stationary with it, while continued movement of the slide 120 will roll out the clutch roll to unclutching position. It sometimes happens that the roll 156 is jarred loose at an early stage of the return movement of the slide 120. In this case provision is made for the positive return of the rack bar 128, the turning iron 72 and the sole support 68. To this end, the slide 120 has formed thereon an abutment 153 which, upon the return movement of the slide, engages the forward end of the rack bar 128 and thus retracts the rack bar; and the retraction of the rack bar, through the gears 136 and 138, drives the turning iron 72 backward. The sole support 68 ordinarily will be returned by its frictional contact with the bars 124 and 128, but should it encounter any accidental resistance, it will be returned positively by the rear end of the rack bar 128 engaging a pin 155 which depends from the under surface of the sole support 68 at a point adjacent to the rear end thereof. The sole support 68 will thus be returned to substantially its initial position, provision being made for reasonable clearance to prevent the rear end of the sole support 68 from being driven positively against the stop-screw 140.

The slide 120 is driven through a link 158 (Fig. 2) from the free end of a lever 160, the opposite end of which lever is journaled upon a shaft 162 secured by a set-screw 164 in the

head 20 of the machine. Formed in the lever 160 is a guideway 166 for a cross-head 168, the cross-head 168 being driven by a crank 170 upon a main driving shaft 172 which is journaled in the head 20. This construction provides for a relatively slow advancing movement of the slide 120 during the turning operation and a relatively quick return at the completion of the turning operation. Motive power for driving the shaft 172 is supplied by a motor 174 (Fig. 1) carried upon a bracket 176 mounted on the standard 22, a control box 178 of usual type being provided for the motor 174. The motor 174, through a belt 180, drives a pulley 182 which is freely rotatable upon a drive shaft 184 journaled in a bracket 186 secured to the standard 22. The web 188 of the pulley 182 is formed to constitute one member of a disk clutch the other member 190 of which is keyed upon the shaft 184 for longitudinal movement thereupon. A spring 192, surrounding the shaft 184 and interposed between a bearing on the bracket 186 and the hub of the clutch member 190, tends to urge the member 190 into clutching position. Control of the rotation of the shaft 184 is effected by a forked lever 194 which straddles the hub of the clutch member 190 and which has a pair of inwardly extending fingers which are received in a peripheral groove in the hub so that upon counterclockwise movement of the lever 194 as viewed in Fig. 2, the clutch member 190 is pulled away from the clutch member 188 against the force of the spring 192. The lever 194 is fulcrumed upon an eccentric 196 which is journaled in the bracket 186. Adjustment of the fulcrum 196 longitudinally of the shaft 184 may be effected by rotation of the eccentric 196 which has a slotted end to enable it to be turned by a screwdriver. A set-screw 198 is provided for maintaining the eccentric 196 in adjusted position. The free end of the lever 194 is controlled by instrumentalities which will later be described. It is desirable that immediately upon the unclutching of the members 188 and 190 the rotation of the shaft 184 be stopped. This is accomplished by means of a brake 200 which is threadedly adjustable in the bracket 186 toward or from the outer face of the clutch disk 190 and which is engaged by the outer face of the clutch disk 190 upon the movement of the latter to unclutching position. Keyed upon the shaft 184 is a worm 202 which meshes with a worm wheel 204 freely rotatable upon the main drive shaft 172. Fixed within the worm wheel 204 are a plurality of clutch plates 206 which alternately engage a plurality of similar clutch plates 208 secured upon a clutch member 210 which is keyed upon the shaft 172. Driving pressure between the plates 206 and 208 is maintained by means of a spring 212 which surrounds the shaft 172 and is interposed between the hub of a clutch cover member

213, which is keyed upon the shaft 172, and the hub of an adjusting wheel 214 threaded upon the end of the shaft 172. Through the adjustment of the pressure of the spring 212, the clutch plates 206 and 208 may be permitted to slip when the operating instrumentalities of the machine encounter an unusual resistance, predetermined in amount, to prevent damage to the shoe. 70

Mechanism is provided for automatically 75 bringing the machine to rest after the completion of the turning operation. This mechanism is controlled by a cam 216 in the form of an eccentric which is rotatable with the shaft 172, being, as shown in Fig. 3, 80 mounted upon the hub of the clutch member 210. A roller 218 (Fig. 2), mounted on the free end of a rocker arm 220, rides upon the periphery of the cam 216, thereby controlling the throw of the rocker arm 220. The rocker arm 220, through a rock-shaft 222 journaled in the bracket 186, controls a second rocker arm 224. The free end of the rocker arm 224 constitutes a latch which is engageable with a plate 226 mounted upon a shoulder 90 formed upon a link 228, which link is pivotally connected to the free end of the clutch control lever 194, the cam 216 being so positioned with respect to the rocker arm 220 that when the shoe turning instrumentalities are 95 at the beginning or the completion of their operative movements, the rocker arm 224 will hold the link 228 against the thrust of the spring 192 and will thereby hold the clutch member 190 out of clutching engagement 100 with the clutch member 188. A tension spring 230 has its ends secured respectively to the link 228 and the rocker arm 224, tending to rotate the rocker arm 224 in a counterclockwise direction as viewed in Fig. 2, and thereby, through the rocker arm 220, to maintain the roll 218 in engagement with the cam 216. The starting of the machine is accomplished by lifting the link 228 so as to raise the shoulder 226 thereon out of engagement 110 with the rocker arm 224, permitting the spring 192 to urge the clutch member 190 into engagement with the clutch member 188. Such lifting of the link 228 is effected by a tripping pawl 232 pivotally mounted upon a control handle or lever 234 which is fulcrumed at 236 upon the bracket 186, the pawl 232 having a slight relative pivotal movement with respect to the lever 232, being urged forwardly therefrom by a compression 115 spring 238. A tension spring 240 interposed between the bracket 186 and the lever 234 urges the lever 234 normally in a counterclockwise direction as viewed in Figs. 1 and 2, tending normally to maintain the pawl 232 below the level of the shoulder 226. The normal position of the lever 234 under the influence of the spring 240 is determined by a stop 237 (Fig. 1). Assuming now that the machine is at rest, it may be started by a 120

125

130

clockwise movement of the lever 234 as viewed in Fig. 2, a stop 235 being provided to limit the movement of the lever 234 in this direction. The effect of such movement is to raise the pawl 232, thereby lifting the end of the link 228 and raising the plate 226 clear of the free or latching end of the rocker arm 224, and thereby effecting engagement of the clutch members 188, 190 and, through such engagement, effecting rotation of the shaft 184, thus causing, through previously described mechanism, rotation of the main drive shaft 172. As the main drive shaft 172 rotates, such rotation taking place in a clockwise direction as indicated by the arrow shown in Fig. 2, the cam 216 will permit a counterclockwise movement of the rocker arm 224 until the free end of the latter travels toward the left beyond the edge of the plate 226. Continued rotation of the shaft 172 will cause the cam 216 to move the rocker arm 220 and thereby the rocker arm 224 in a clockwise direction, and such movement will cause the free end of the rocker arm 224 to engage the edge of the plate 216 and to pull the link 228 bodily toward the right, thereby moving the clutch member 194 away from the clutch member 188 and into engagement with the brake 200, stopping the operation of the machine definitely at the end of a cycle. The lever 234, meanwhile, and immediately upon release of the grasp of the operator, has been restored by the spring 214 to its normal position, and the above-described movement of the link 228 toward the right will cause the plate 226 to pass above the pawl 232 and thereby restore the mechanism to readiness for a further operation. Even if, however, the operator should inadvertently retain his grasp upon the control lever 234, the above-described mechanism will not initiate a second cycle of operation, because the above-described movement of the link 228 will merely serve to push the pivotally mounted pawl 232, now in raised position, to the right against the force of the spring 238. Release of the control lever 234 will then lower the pawl 232, permitting it to pass under the plate 226 to its normal position of readiness to initiate another cycle.

If unusual circumstances should render manipulation or adjustment of the shoe necessary, or if some other emergency should arise, the operator can stop the machine at any point in its cycle by depressing a treadle 241 (Fig. 1), thereby exerting an upward thrust through a rod 239 which is pivotally connected to one arm of a bell-crank 243 (Fig. 2) which is freely rotatable upon the shaft 222. The bell-crank 243 is thereby rotated in a clockwise direction, as viewed in Fig. 2, and its other arm will engage the plate 226, which extends transversely of the link 228 to enable it to be thus engaged. If now, the link 228 should be in any position other than

that at which it holds the clutch member 190 against the brake 200 and away from the clutch member 188, the depression of the treadle 241 will move the link 228 to such position. Upon release of the treadle 241, the link 228 will be restored to the control of the cam 216, and the operation of the machine will be resumed at whatever point in the cycle it was stopped.

As above stated, mechanism is provided for holding the forepart spreader 70 down during the advance of the turning irons 68 and 72. Such mechanism is controlled by a cam 242 (Figs. 2 and 3) in the form of a cylindrical segment which is concentric with the axis of the shaft 172 and which is mounted upon a cam disk 244 carried upon the shaft 172. A roll 246, adapted to ride upon the outer surface of the cam 242, is carried upon one arm of a bell-crank 248 fulcrumed upon the shaft 162, the other arm of the bell-crank 248 being pivotally connected to a link 250 (Figs. 1 and 2) which has its upper end pivoted to the bearing 76. When the forepart spreader 70 is in raised or inoperative position, the roll 246 assumes a position within the segmental cam 242. When the operator lowers the forepart spreader, the roll 246 is moved, through the bell crank 248, outwardly to a position wherein the periphery of the roll 246 is at substantially the same radial distance from the axis of the cam 242 as the outer periphery of the cam itself is. The segmental cam 242 has its opening so positioned that when the machine is at rest, the roll 246 may pass therethrough. The operation of the machine then having been initiated, the rotation of the shaft 172 will bring the cam 242 into a position wherein the roll 246 will ride upon the periphery of the cam 242 thereby preventing return of the bell-crank 248 to its former position and will thus hold the members which carry the forepart spreader 70 in operative position. As the cycle of operation of the machine nears completion, the cam 242 will be brought into such position that the roll 246 may enter within the opening of the cam segment, thereby permitting the forepart spreader 70 to be raised by the force of a torsion spring 252 which surrounds the hub of the bell-crank 248. One end of the spring 252 acts against a flanged portion of the bell-crank 248, tending to rotate the bell-crank 248 into position to raise the bearing 76, the opposite end of the spring 252 being anchored in a castellated nut 254 which is threaded upon the end of the shaft 162 and which is held in adjusted position thereupon by a cotter-pin 256.

As shown in Fig. 12, the forepart spreader 70 has a slight downward inclination toward its toe end, and the sole of the shoe S is interposed between the forepart spreader 70 and the sole support 68. The most satisfactory co-operation between the turning

iron 72 and the forepart spreader 70 is obtained when the toe end of the latter is spaced no further from the upper surface of the sole support 68 than is required by the thickness of the sole of the shoe S. In order to maintain the forepart spreader 70 in such a position without resorting to delicate heightwise adjustment for soles of varying thickness, and also to accommodate inequalities of thickness in various portions of a sole, the above-mentioned pivotal connection between the link 250 and the bell-crank 248 includes a sleeve 251 (Fig. 2) through which the link 250 freely slides. The sleeve 251 is threaded through a block 253 which is pivotally connected to the bell-crank 248. Surrounding the link 250, and interposed between the sleeve 251 and a nut threaded on the lower end of the link 250 is a compression spring 255 which serves yieldingly to maintain the toe end of the forepart spreader down upon the sole of the shoe S. When, now, the link 250 is moved upwardly by the spring 252, and is stopped by the roll 246 engaging the inner surface of the cam 242, the inertia of the upwardly moving parts will be absorbed by the spring 255.

The above-mentioned means for locking the heel cup turret 44 in operative position is controlled by the rotation of the main shaft 172 through the instrumentality of a roller 258 (Fig. 2) and a half round pin 260 mounted adjacent to each other upon the face of the cam disk 244 which is opposite the cam 242. The pin 260 is held in adjusted position by a set screw 261. The flat surface of the half round pin 260 is engageable with a concavely formed end portion of a lever 262 which is secured on a shaft 264 fixed in the head 20. Angular adjustment of the lever 262 about the shaft 264 is provided by a pair of set screws 266 threaded through the hub of the lever 262 and having their ends abutting squared-off surfaces formed upon either side of the shaft 264. Mounted upon the shaft 264 and held against rotation with respect thereto by a key 268 (Fig. 7) is a hub 270 of a clutch actuating member which comprises a flange 272 depending from the hub 270. A locking bar 274 is pivotally mounted upon one end of an arm 276 which is integral with the lever 46, whereby locking of the bar 274 when the turret 44 is in operative position will serve to maintain the turret in such position. The locking bar 274 is supported by a cylindrical rod 278, the bar 274 being freely slideable thereover. Above both the rod 278 and the locking bar 274 is an abutment 280 having an inclined lower face and between this inclined lower face and the upper face of the bar 274 is interposed a clutch roll 282. Extending outwardly from the face of the depending flange 272 is a pair of fingers 284 for engaging the roll 282 upon each side thereof to move it into or out of a

position wherein the inclined under face of the abutment 280 will cause the roll 282 to exert a clutching pressure upon the locking bar 274, the latter being supported against the pressure of the roll 282 by the rod 278. No yielding movement of the locking bar 274 is necessary to develop the full clutching effect of the rod 282, and lost-motion tending to loosen the clamping grip of the members 24 and 42 upon the heel seat of the shoe is thus eliminated. Secured upon the ends of the fingers 284 is a retaining plate 286, the roll 282 being held against movement in a direction transverse to the bar 274 by the retaining plate 286 and the depending flange 272. In order to provide for up or down adjustment of the abutment 280 so that the roll 282, when in clutching position, will be substantially over the rod 278, the abutment 280 is not mounted directly upon the head 20 but is journaled upon an eccentric peripheral portion 288 of a sleeve 290 which is mounted for rotation in the head 20, the sleeve 290 constituting a bearing in which is journaled the shaft 264. Formed on the end of the sleeve 290 is a flange 292 having formed therein a pair of arcuate slots 294 (Fig. 1) which are concentric with the axis of the shaft 264 and which may be clamped by a pair of clamping bolts 296 in any desired position of adjustment. Rotation of the sleeve 290 will, through its eccentric portion 288, serve to raise or lower the abutment 280 as may be desired, rotation of the abutment being prevented by a pin 298 which engages a vertical slot 300 formed in the abutment 280. A spring 302 tends to urge the lever 262 upwardly and to throw the clutch roll 282 into clutching position to lock the bar 274 and thereby the heel cup turret 44. Assuming the turning of the heel portion of the shoe to have been completed, the operator, while still holding his foot upon the treadle 54, initiates the operation of the forepart turning instrumentalities through the control lever 234 in the manner previously described. At the beginning of the rotary movement of the shaft 172, the flat surface of the half round pin 260 is in engagement with the concavely formed portion of the free end of the lever 262 and holds the lever in unlocking position against the force of the spring 302. After a relatively slight rotation of the shaft 172, however, the half round pin 260 is carried beyond the end of the lever 262, allowing the latter to be snapped by the spring 302 into locking position and thereafter rendering it unnecessary for the operator to retain his foot on the treadle 54. After the forepart turning instrumentalities have completed their operation upon the shoe and as they are being restored to their initial positions, the roller 258 engages and rides under the concavely formed portion of the end of the lever 262, thereby unlocking the

clutch roll 282 and releasing the heel cup 44, which is now free to return under the influence of the spring 56 to its inoperative position. The purpose of the half round 5 pin 260 is to provide a more sudden release of the lever 262 than could be accomplished by relying upon the roller 258, since the latter, by reason of its appreciable diameter, would necessarily effect a slower release for 10 the lever 262 than the half round pin 260. The advantage of the quick release for the lever 262 is that it insures immediate and reliable clutching engagement of the roll 282. In order to enable the operator to release the 15 heel cup turret 44 at any point of the cycle of operation of the machine, the lever 262 is extended beyond the shaft 264, the right-hand end of the lever 262, as viewed in Fig. 2, being shaped to provide a convenient hand 20 grip 306. By pulling up the hand grip 306 against the force of the spring 302 the roll 282 may be released at any time and the turret 44 unlocked.

A stationary hook-shaped member 304 is 25 provided for use in smoothing out manually any wrinkles that may remain in the toe portion of a shoe after the shoe has been turned by the above described instrumentalities.

30 In the operation of the machine, the heel portion of the shoe S is placed over a selectively positioned heel cup 42 with the upper of the shoe S extending outside of the cup 42. Depression of the treadle 54 thereupon 35 serves to swing the turret 44 and the heel cup with the shoe S upon it toward a selectively positioned stationary member 24, causing the latter first to be engaged by the heel seat of the sole of the shoe and then to 40 be received within the heel cup 42, the heel seat thus being forced into the cup and the upper of the shoe being turned over the edges of the cup. The operator, with his 45 foot still on the treadle 54 to maintain a clamping pressure upon the heel seat of the shoe S between the stationary member 24 and the base of the heel cup 42, then bends the sole of the shoe S over the end of the sole support 68 and inserts the forepart 50 spreader 70 into the forepart of the shoe. Still keeping the heel seat of the shoe 55 clamped, he starts rotation of the shaft 170 by a movement of the handle 284. As soon as the shaft 170 has rotated through a small 60 fraction of a revolution, the segmental cam 242 will operate to maintain the forepart spreader 70 down without further attention on the part of the operator, and the pin 260 will be carried beyond the end of the lever 262, allowing the latter under the influence 65 of the spring 302 to lock the heel cup 42 in heel-seat clamping position and thereby permitting the operator to withdraw his foot 70 from the treadle 54. Continued rotation of the shaft 172 advances the slide 120, causing

the turning iron 72 to engage the toe end of the shoe S. The resistance which the turning iron 72 encounters upon engagement with the toe end of the shoe causes both the sole support 68 and the bar 128 to be clamped 70 simultaneously to the slide 120 and thus to be advanced in unison with the slide 120, while the bar 128, operating through the gears 138 and 136, drives the turning iron 72 at twice the speed of the sole support 68. As 75 the turning iron 72 advances, the forepart spreader 70 recedes, and the shoe S is progressively turned and transferred right-side out upon the sole support 68. Figs. 12 and 80 13 show the positions of the shoe S and of the turning instrumentalities at earlier and later stages, respectively, of the turning operation. As soon as the shoe has been turned, continued rotation of the shaft 172 85 serves to retract the slide 120 with the turning iron 72 and the sole support 68 to their initial positions and also to release the forepart spreader 70 to permit it to swing upwardly out of the way. During the retraction of the slide 120 the rotation of the shaft 90 172 serves also to unlock the turret 44 and to release the heel seat of the shoe S from the clamping grip of the heel cup 42 against the stationary member 24.

Having described my invention, what I 95 claim as new and desire to secure by Letters Patent of the United States is:—

1. A shoe turning machine having, in combination, shoe clamping means, shoe turning means, means actuated by said turning means 100 to lock said clamping means in clamping position to hold a shoe during the operation of said turning means upon the shoe, and operator-controlled means for unlocking said clamping means to release the shoe independently of said shoe turning means at any time during the operation of said shoe-turning means.

2. A shoe turning machine having, in combination, shoe clamping means, shoe turning 110 means, a roll clutch constructed and arranged to lock said clamping means in clamping position, and means actuated by said turning means for actuating said roll clutch to hold a shoe clamped by said clamping means during the operation of said turning means upon the shoe.

3. A shoe turning machine having, in combination, cooperating members for turning the heel portion of a shoe, means for turning the forepart of the shoe, means for actuating said forepart turning means, and means controlled by said actuating means and including a roll clutch for locking said heel turning members to clamp the heel seat of the sole of the shoe to hold the shoe during the operation of said forepart turning means.

4. A shoe turning machine having, in combination, a pair of co-operating members for turning the heel portion of a shoe, one of 130

- said members being stationary and the other being movable, means for turning the forepart of the shoe, means for actuating said forepart turning means, a member connected 5 to said movable heel turning member for controlling the movement thereof, a pair of relatively inclined abutments, one of said abutments being stationary and the other being carried upon said controlling member, a clutch roll interposed between said abutments, means for supporting said controlling member against the thrust of said clutch roll, and means controlled by said actuating means for moving said roll into engagement 10 with both of said abutments to clutch said controlling member for locking said movable heel turning member to clamp the heel seat of the sole of the shoe to hold the shoe during the operation of said forepart turning means.
- 20 5. A shoe turning machine having, in combination, shoe turning means, means for driving said shoe turning means, control mechanism interposed between said driving means and said shoe turning means, and a control handle normally engageable with said control mechanism, said control mechanism being constructed and arranged to be disengaged from said control handle by movement of said control handle from one position to another and thereupon to engage said driving means with said shoe turning means, and thereafter to cause said shoe turning means to move through a predetermined cycle.
- 25 6. A shoe turning machine having, in combination, shoe turning means, means for driving said shoe turning means, control mechanism interposed between said driving means and said shoe turning means, a control handle associated with said control mechanism, 30 said control mechanism being constructed and arranged, upon movement of said control handle from one position to another, to engage said driving means with said shoe turning means, and thereafter, independently of the position of said control handle, to cause 35 said shoe turning means to move through a predetermined cycle, and operator-controlled means associated with said mechanism for disengaging said driving means from said 40 shoe turning means.
- 45 7. A shoe turning machine having, in combination, shoe turning means, means for driving said shoe turning means, a brake for stopping said shoe turning means, and control mechanism for engaging said driving means with said shoe turning means to cause said shoe turning means to move through a predetermined cycle, said control means being operable thereupon to disengage said driving 50 means from said shoe turning means and to actuate said brake to stop the movement of said shoe turning means definitely at the end of the cycle.
- 55 8. A shoe turning machine having, in combination, a turret, a plurality of heel turning 60 members secured to said turret, means for securing said turret in one of a plurality of predetermined positions about the axis of said turret, and means for adjusting said heel turning members with respect to said turret about the axis of said turret.
- 65 9. A device for use in turning shoes, comprising a shoe turning member having a shank, a support having a socket for receiving the shank of said turning member, means adjustable in a direction lengthwise of said shank for determining the desired lengthwise position of said shank in said socket, and means for clamping said shank in said adjusted position in said socket.
- 70 10. In a shoe turning machine, a turret, a plurality of heel turning members extending radially from said turret, adjustable means for determining a desired radial distance between the axis of said turret and each of said heel turning members, and means for securing said heel turning members to said turret in positions determined respectively by said adjustable means.
- 75 11. In a shoe turning machine, a forepart spreader for holding the forepart of a shoe, a carrier for said forepart spreader constructed and arranged to guide said forepart spreader in a predetermined path of movement, and adjusting means constructed and arranged to provide for rotary adjustment of said spreader about the longitudinal axis of said spreader and to secure said spreader to said carrier.
- 80 12. In a shoe turning machine, a forepart 90 spreader for holding the forepart of a shoe, a carrier for said forepart spreader constructed and arranged to guide said forepart spreader in a predetermined path of movement, a member pivotally mounted upon said carrier to which member said forepart spreader is secured, said member having a slot formed therein, an eccentric pin journaled in said carrier and engaging said slot for rocking said carrier to tilt said forepart spreader to a desired position of adjustment, and means for locking said member to said carrier to maintain said forepart spreader in said desired position.
- 85 13. In a shoe turning machine a forepart 95 spreader for holding the forepart of a shoe, a carrier for said forepart spreader constructed and arranged to guide said forepart spreader in a predetermined path of movement, and adjusting means constructed and arranged to guide said forepart spreader for translatory adjusting movement with respect to said carrier in a direction transverse to the direction of said predetermined path and to secure said forepart spreader to said carrier in a desired position of adjustment.
- 90 14. A shoe turning machine comprising two members constructed and arranged to co-operate in turning a shoe, and operating 100
- 95
- 105
- 110
- 115
- 120
- 125
- 130

- mechanism for said members constructed and arranged to impart an operative movement to one of the members and, simultaneously with the initiation of said operative movement, to move the other turning member at a different speed from that of the first member to cause it to co-operate with the first member.
15. A shoe turning machine, comprising a pair of members constructed and arranged upon relative movement to co-operate with each other in turning a shoe, a carrier upon which said members are movably mounted, means for advancing said carrier, means for connecting one of said members to said carrier to cause said member to be advanced with said carrier, and means constructed and arranged to advance the other member simultaneously with said connecting of the first member to said carrier and at a speed different from the speed of the first member.
16. A shoe turning machine, comprising means for supporting a shoe to be turned, a pair of members constructed and arranged upon relative movement to co-operate with each other and with said shoe supporting means in turning a shoe, means for advancing said carrier, means for advancing one of said members in unison with said carrier into engagement with the shoe on said supporting means; and means operable by said one member upon encountering the resistance of the shoe for connecting the other said member to said carrier and simultaneously with said connecting for advancing said one member at a speed which is greater than the speed of advance of said carrier.
17. A shoe turning machine, comprising a support about which the sole of a shoe may be bent, a turning iron adapted to engage the toe portion of the shoe, a carrier upon which said sole support and said turning iron are movably mounted, means for advancing said carrier, means for connecting said sole support to said carrier to cause said sole support to be advanced against the shoe, and means constructed and arranged to advance said turning iron simultaneously with said connecting of said sole support to said carrier and at a speed which is greater than the speed at which said sole support is advanced by said carrier.
18. A shoe turning machine, comprising stationary means for clamping the heel seat of a shoe, a forepart spreader adapted to be inserted into the forepart of the shoe, a support about which the sole of the shoe may be bent, a turning iron, a slide upon which said sole support and said turning iron are movably mounted, means for advancing said slide, means for imparting the movement of said slide to said turning iron to bring said turning iron into engagement with the toe end of the shoe, means operable by said turning iron upon encountering the resistance of
- the shoe for connecting said sole support to said slide and simultaneously with said connecting for advancing said turning iron at twice the speed of said slide, and means for guiding said forepart spreader in the path of movement of said turning iron.
19. A shoe turning machine, comprising a slide, mechanism for actuating the slide, a turning iron and a sole support carried by the slide, and mechanism for initially causing said turning iron to move in unison with the slide until said turning iron encounters resistance and for thereupon causing simultaneously said sole support to be clutched to said slide and said turning iron to be operated at a greater rate of speed.
20. A shoe turning machine, comprising a support about which the sole of a shoe may be bent, a turning iron adapted to engage the toe portion of the shoe, a slide upon which said sole support and said turning iron are movably mounted, means for reciprocating said slide, means for imparting an advancing movement from said slide to said sole support and to said turning iron at different speeds respectively during the advance of said slide to cause said sole support and said turning iron to co-operate with each other in turning a shoe, and positive means for imparting a return movement from said slide to said turning iron and to said sole support during the return of said slide.
21. A shoe turning machine, comprising a carrier, a plurality of shoe turning instrumentalities movably carried upon said carrier, means for reciprocating said carrier, means for advancing said instrumentalities at various speeds respectively during the advance of said carrier to cause said instrumentalities to co-operate in turning a shoe, and driving connections between said instrumentalities and said carrier operable upon the return movement of said carrier positively to return said instrumentalities.
22. In a shoe turning machine, a member constructed and arranged to assist in the turning of a shoe, a carrier for said member, a support for said carrier, said carrier being freely movable longitudinally with respect to said support, a pivotal mounting for said support whereby the latter may be tilted to bring said member into and out of operative position, and means for cushioning the longitudinal downward movement of the carrier which takes place upon upward tilting of said support.
23. In a shoe turning machine, a member constructed and arranged to be inserted into the forepart of a shoe to hold the shoe in a position for turning a carrier for said member, a bearing through which said carrier is longitudinally movable, a pivotal mounting for said bearing whereby the latter may be tilted to bring said member into and out of operative position, a stationary abutment.

and means interposed between said carrier and said abutment for cushioning the downward movement of said carrier which takes place upon upward tilting of said support.

5. 24. A shoe turning machine, comprising a pair of members constructed and arranged to co-operate by relative movement in turning a shoe, driving means for said members, a driving connection between said driving means and one of said members, a normally disengaged driving connection between said members, and means for simultaneously effecting a driving engagement between said driving means and the other of said members.
10. 15. and engaging said driving connection between said members, thereby driving said one member through said other member.

20. 25. A shoe turning machine, comprising a pair of members constructed and arranged to co-operate by relative movement in turning a shoe, driving means for said members, a driving connection between said driving means and one of said members, a normally disengaged driving connection between said members and a roll clutch constructed and arranged to effect a driving engagement between said driving means and the other of said member and to engage said driving connection between said members, thereby driving said one member through said other member.

25. 30. 35. A shoe turning machine, comprising a pair of members constructed and arranged to co-operate by relative movement in turning a shoe, driving means for said members, means for establishing driving engagement between said driving means and one of said members, normally inoperative means for insuring a predetermined speed ratio between said members, and means for simultaneously establishing driving engagement between said driving means and the other of said members and rendering operative said normally inoperative means, thereby driving 40. 45. said one member at said predetermined speed ratio to said other member.

30. 35. 40. 45. 50. 55. 60. 65. 27. A shoe turning machine, comprising a pair of members constructed and arranged to co-operate by relative movement in turning a shoe, a carrier upon which said members are movably mounted, means for advancing said carrier, means for imparting the movement of said carrier to one of said members, normally inoperative means for insuring a predetermined speed ratio between said members, and means for simultaneously securing the other of said members to said carrier and rendering operative said normally inoperative means, thereby driving said one member at said predetermined speed ratio to said other member.

28. A shoe turning machine, comprising a pair of members constructed and arranged to co-operate by relative movement in turning a shoe, a bar, a carrier upon which said mem-

bers and said bar are movably mounted, means for advancing said carrier, means for imparting the movement of said carrier to one of said members, means for insuring a predetermined speed ratio between said one member and said bar, and means for securing the other of said members and said bar to said carrier, thereby causing said one member to be advanced at said predetermined speed ratio to said other member and to said carrier.

29. A shoe turning machine, comprising a pair of members constructed and arranged to cooperate by relative movement in turning a shoe, a bar, a carrier upon which and with respect to which said members and said bar are movably mounted, means for advancing said carrier, means for imparting the movement of said carrier to one of said members, means for insuring a predetermined speed ratio between said one member and said bar, and a clutch for clamping together said carrier, said bar, and the other of said members, thereby causing said one member to be advanced at said predetermined speed ratio to said other member and to said carrier.

30. A shoe turning machine, comprising a pair of members constructed and arranged to cooperate by relative movement in turning a shoe, means for driving said members, normally inoperative means for insuring a predetermined speed ratio between said members, means interposed between said driving means and one of said members for advancing said one member into engagement with a shoe to be turned, and means operable by said one member upon encountering the resistance of the shoe for connecting the other member to said driving means and for simultaneously rendering operative said normally inoperative means for insuring a predetermined speed ratio between said members, thereby causing said other member to be advanced in unison with said driving means and causing said one member to be advanced by said driving means at said predetermined speed ratio to said other member.

31. A shoe turning machine, comprising a pair of members constructed and arranged to cooperate by relative movement in turning a shoe, driving means for said members, means for establishing driving engagement between said driving means and one of said members, a pair of gears coaxially mounted and secured together for rotation in unison with each other, one of said gears having driving engagement with said one member, and means for effecting simultaneously driving engagement between said driving means and said other member and between said other member and said other gear, thereby driving said one member at a speed ratio to said other member determined by the pitch diameters of said gears.

32. A shoe turning machine, comprising a

turning iron, a support about which may be bent the sole of a shoe to be turned, means for driving said turning iron and said sole support, a bar, a connection constructed and arranged to insure a predetermined speed ratio between said turning iron and said bar, means interposed between said driving means and said turning iron for advancing the latter into position for engagement with the toe of the shoe, and means operable by said turning iron upon encountering the resistance of the shoe for securing said sole support both to said driving means and to said bar, thereby causing said sole support to be advanced in unison with said driving means and causing said turning iron to be advanced by said driving means operating through said bar and through said connecting means at said predetermined speed ratio with respect to said sole support.

33. A clutch comprising a clutch roll and a clamping member between which an article may be clamped, an abutment having an inclined operative surface arranged upon movement of said roll relative thereto to cause said roll to exert a thrust against the article to clamp the article against said clamping surface, an eccentrically mounted support for said abutment, means for rotating said support and thereby adjusting said abutment to vary the distance between said operative surface and said clamping member, and means for preventing rotation of said abutment about the axis of rotation of said support.

34. A shoe-turning machine comprising a pair of members constructed and arranged to co-operate by relative movement in turning a shoe, means for holding the shoe in a position wherein the sole of the shoe is bent around the end of one of said members, means for advancing the other member into engagement with the toe portion of the shoe, and means for then initiating simultaneously the advance of both members at a definite speed ratio of the one to the other.

35. A shoe-turning machine comprising a pair of members constructed and arranged to co-operate by relative movement in effecting a turning operation upon the forepart of a shoe, means for holding the shoe in a position wherein the sole of the shoe is bent around the end of one of said members, means for advancing the other member into engagement with the toe portion of the shoe, and means for then initiating simultaneously the advance of both members at a definite speed ratio, the speed of the member which engages the toe portion of the shoe being twice the speed of the member about which the sole is bent.

36. A shoe-turning machine comprising a pair of members constructed and arranged to co-operate by relative movement in effecting a turning operation upon the forepart

of a shoe, means for holding the shoe in a position wherein the sole of the shoe is bent around the end of one of said members, means for advancing the other member into engagement with the toe portion of the shoe, and means operable by said other member upon encountering the resistance of the toe portion of the shoe to initiate simultaneously the advance of both members at a definite speed ratio, the speed of the member which engages the toe portion of the shoe being greater than the speed of the member about which the sole is bent.

37. A shoe-turning machine comprising a pair of members constructed and arranged to co-operate by relative movement in turning a shoe, driving means for said members, a driving connection between said driving means and one of said members for causing said member to be driven at the same speed as said driving means, a normally inoperative driving connection between said driving means and said member for causing said member to be driven at a speed different from the speed of said driving means, and means for simultaneously rendering operative said normally inoperative driving connection and connecting the other of said turning members to said driving means.

38. A shoe-turning machine comprising a pair of members constructed and arranged to co-operate by relative movement in turning a shoe, a bar, a carrier upon which said members and said bar are movably mounted, means for advancing said carrier, means for imparting the movement of said carrier to one of said members to bring said one member into engagement with the shoe, means for insuring a predetermined speed ratio between said member and said bar, and means operable simultaneously to clamp the other of said members and said bar to said carrier, thereby causing said other member to be advanced with said carrier and causing said first-named member to be advanced relatively to said other member in said predetermined speed ratio.

39. A shoe-turning machine comprising a pair of members constructed and arranged to co-operate by relative movement in turning a shoe, a bar, a carrier upon which said members and said bar are movably mounted, means for advancing said carrier, means for imparting the movement of said carrier to one of said members to bring said one member into engagement with the shoe, means for insuring a predetermined speed ratio between said one member and said bar, a roll clutch constructed and arranged simultaneously to clamp the other said member and said bar to said carrier, and means actuated by said one member upon encountering the resistance of the shoe to move said clutch into clutching position, thereby causing the other said member to be advanced with said carrier and caus-

ing said one member to be advanced at said predetermined speed ratio to said other member.

40. A shoe-turning machine comprising a pair of members constructed and arranged to co-operate by relative movement in turning a shoe, a bar, a carrier upon which said members and said bar are movably mounted, means for advancing said carrier, means for imparting the movement of said carrier to one of said members, means for insuring a predetermined speed ratio between said one member and said bar, and means for clamping the other said member and the bar each though the other to said carrier, thereby causing the other said member to be advanced with said carrier and said one member to be advanced at said predetermined speed ratio to the other said member.

20. 41. In a shoe-turning machine, a member adapted to extend into the forepart of a shoe, a support for the sole of the shoe, yieldable means urging said member against the sole of the shoe to press the sole against said support, and means co-operating with said member and with said support to turn the forepart of the shoe.

42. In a shoe-turning machine, a support about which the sole of a shoe may be bent, a forepart spreader adapted to extend into the forepart of the shoe, resilient means urging said member against the sole of the shoe to press the sole against said support, and means co-operating with said member and with said support to turn the forepart of the shoe.

43. In a shoe-turning machine, a support about which the sole of a shoe may be bent, a forepart spreader adapted to extend into the forepart of the shoe and arranged to be movable between operative and inoperative positions, resilient means urging said forepart spreader when in operative position against the sole of the shoe to press the sole against said support and serving also to cushion the shock of the forepart spreader when the latter is moved to inoperative position, and means co-operating with said member and with said support to turn the forepart of the shoe.

50. In testimony whereof I have signed my name to this specification.

WILLIAM D. THOMAS.
